US0D1021923S

(12) **United States Design Patent** (10) **Patent No.:** **US D1,021,923 S**
(45) **Date of Patent:** **** Apr. 9, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Mikio Inose**, Cupertino, CA (US);
Tiffany Jon, Sunnyvale, CA (US);
Christopher Moore, San Francisco, CA (US);
Marcel van Os, Santa Cruz, CA (US);
Emanuele Vulcano, San Francisco, CA (US); **Eleanor Cady Wachsmann**, San Francisco, CA (US)

(73) Assignee: **Apple Inc.**, Cupertino, CA (US)

(**) Term: **15 Years**

(21) Appl. No.: **29/823,180**

(22) Filed: **Jan. 14, 2022**

Related U.S. Application Data

(63) Continuation of application No. 29/707,723, filed on Sep. 30, 2019, now Pat. No. Des. 941,302, which is a continuation of application No. 29/622,308, filed on Oct. 16, 2017, now Pat. No. Des. 861,705, which is a continuation of application No. 29/540,702, filed on Sep. 26, 2015, now Pat. No. Des. 800,143, which is a continuation of application No. 29/423,888, filed on Jun. 6, 2012, now Pat. No. Des. 739,859.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
